UNITED STATES PATENT OFFICE.

TOM L. STEELE, OF DALHART, TEXAS.

BRIDLE ATTACHMENT.

1,322,367.

Specification of Letters Patent.

Patented Nov. 18, 1919.

Application filed June 17, 1918. Serial No. 240,437.

To all whom it may concern:

Be it known that I, Tom L. Steele, a citizen of the United States, residing at Dalhart, in the county of Dallam and State of Texas, have invented certain new and useful Improvements in Bridle Attachments, of which the following is a specification.

This invention relates to improvements in harness and it is the principal object of the invention to provide a novel form of connection for the usual blind or "winker" brace of a bridle, whereby the breaking of the brace due to the relative movement between the same and the blind of the bridle, caused by the motion of the horse's head when in action, thus providing a durable and strong connection as well as effecting a material saving upon part of a user.

Another and equally important object of the invention is to provide a connection of the character described which is simple in construction and which can be attached to the conventional form of bridle with but slight alteration thereto.

Other and further improvements and novel details in the construction and arrangement of parts will be appreciated from the description to follow, which for a clear understanding of the invention should be considered in connection with the accompanying drawings forming a part hereof and wherein the preferred embodiment of the invention is shown for the purpose of illustration.

35 In the drawings:

Figure 1 is a perspective of the blinds of a bridle and portions of the blind or "winker" braces, portions of one of the blinds being broken away,

Fig. 2 is a fragmentary detail of the same taken approximately on the line 2-2 of Fig. 3, a portion of the blind being removed, and

Fig. 3 is a fragmentary sectional view therethrough.

Having more particular reference to the drawings, in connection with which like reference characters will designate corresponding parts throughout the several views, *b* represents the several blinds of a bridle and *b'* the blind or "winker" braces therefor, it of course being understood in this connection that said braces are connected at certain of their ends to the blinds while the

remaining ends thereof converge and are 55 connected to the headstrap of a bridle.

The improved connection includes pivotally joined elements designated by the numerals 1 and 2, the element 1 being formed with a curved shoulder or bearing portion 60 3 while the upper end of the same is apertured and reduced as at 4. As will be noted, the adjacent end of the element 2 is bifurcated and has a pocket 5 arranged in the same between the bifurcated parts for receiving the reduced end 4 therein and for limiting the pivotal movement of the same and said element 1. The element 2 is also provided with a suitable form of socket for receiving the adjacent end of the blind brace 70 *b'*, which brace can be connected thereto by a rivet 6 or similar fastening device. To pivotally connect the adjacent portions of the connecting elements 1 and 2, a pivot pin 7 is passed therethrough and is formed to 75 prevent undue displacement or movement. To allow the connection to be engaged with the blind *b*, the lower portion thereof is formed with a shank which is apertured and which is arranged adjacent the usual metal 80 insert 8 of the ordinary blind *b* and is secured thereto by passing rivets through the same and said blind, said rivets being indicated by the numeral 9.

From the foregoing, it will be readily 85 understood by workers skilled in the art that I have provided an exceedingly simple and effective form of connection for the "winker" braces and blinds of a bridle, whereby the breaking of the brace will be prevented irrespective of the extent of wear of the same. Due to the pivotal connection between the several elements 1 and 2 of said connection, it will be readily understood that the motion of the horse's head when in action will 95 be compensated for and as a consequence the continuous flexing of the "winker" brace at the point of its connection with the blind will be entirely eliminated.

The construction of my improved device 100 is such as to permit its attachment to the usual form of bridle blind and "winker" brace with but slight alteration thereto. However, if desired, the same can of course be applied to a bridle during the making or 105 manufacturing of the same.

Manifestly, the construction shown is capable of considerable modification and such

modification as is within the scope of my claims, I consider within the spirit of my invention.

I claim:

- 5 1. In combination with a blind and blind brace of a bridle, a hinged connection therefor including an element having one end thereof reduced and a bifurcated element formed with a pocket for receiving the reduced end of said first element therein and between said bifurcated parts, means for pivotally connecting the adjacent portions of said elements, said connection having its opposite ends connected to the blind and the brace.
- 10 2. The combination with winker braces and blinds of a bridle, of pivotal connec-

tions between the braces and blinds comprising thimble-like members fastened upon the braces and having bifurcated ends, the bifurcations being formed with recesses medially thereof, members fixed to the blinds and having ends engaged in the bifurcations, reduced portions formed on the ends of less size than the recesses and received therein, and pivots passed transversely through the bifurcations in the thimble-like members and engaged in the last named members for pivotally connecting the latter with the thimble-like members.

In testimony whereof, I affix my signature hereto.

TOM L. STEELE.
